UNITED STATES PATENT OFFICE.

JOHN J. LONSWAY, OF FOSTORIA, OHIO.

PORTRABLE RAIL-DRILL.

1,380,991.

Specification of Letters Patent. Patented June 7, 1921.

Application filed April 11, 1918. Serial No. 228,002.

To all whom it may concern:

Be it known that I, JOHN J. LONSWAY, a citizen of the United States, residing at Fostoria, in the county of Seneca and State of Ohio, have invented a new and useful Portable Rail-Drill, of which the following is a specification.

This invention has reference to portable rail drills, and is an improvement upon the rail drill for which Reissue Letters Patent Number 14,196, were granted to me on September 26, 1916.

The object of the invention is to simplify the construction and to adapt the rail drill for work upon electric railroads without interruption of the electric current, especially that used for operating signals.

In accordance with the invention and to meet certain conditions, but two drill shafts are employed and these are arranged in alinement and project in opposite directions, permitting double bonding with only one drill hole in the web of each rail. Improved thrust bearings for each shaft are provided, whereby the thrust block or collar on the shaft is lodged between ball bearings. Furthermore, means are provided whereby the clamp bars for engaging the rails to back up the drills are carried through side bars serving to support them.

In order to prevent short circuiting signal currents when it becomes necessary to repair the tracks, as when replacing rails and subsequently boring them, the two ends of the rail-drilling machine are insulated one from the other so that the current may remain in the track without liability of unintentionally working the signals.

The invention will be best understood from a consideration of the following detailed description taken in connection with the accompanying drawings forming part of this specification, with the understanding, however, that the invention is not confined to any strict conformity with the showing of the drawings but may be changed and modified so long as such changes and modifications mark no material departure from the salient features of the invention as expressed in the appended claims.

In the drawings:

Figure 1 is a side elevation of the rail-drilling machine mounted on and between

the rails of a railway track, said rails being shown in cross section. 55

Fig. 2 is a plan view of the structure shown in Fig. 1.

Fig. 3 is a left hand end elevation of the structure shown in Fig. 1, but confined to the end only of the machine, distant parts 60 being omitted.

Fig. 4 is a longitudinal section of the end of the machine opposite to the showing of Fig. 3 and indicated by the section line 4—4 in Fig. 2. 65

Fig. 5 is a plan view of a portion of the machine, with some parts in section, and omitting the prime mover and adjacent parts.

Fig. 6 is a longitudinal vertical section 70 on the line 6—6 of Fig. 5.

Fig. 7 is a section on the line 7—7 of Fig. 5, but drawn on a larger scale.

Figs. 8, 9 and 10 are sections on the lines 8—8, 9—9 and 10—10 of Fig. 7. 75

Referring to the drawings, there is a main frame composed of side beams 1 and 2, spaced apart crosswise of the machine or lengthwise of the track when the machine is mounted thereon. At suitable intervals 80 there are cross bars 3 connecting the side beams and also serving as supports for certain parts of the mechanism. The side beams are each discontinuous longitudinally and the parts are joined at one side of the 85 center by coupling plates 4 so that one end of the frame may be removed from the other end to permit boring of the rails where the available space is less than the width between the track rails 5. This feature is fully 90 described in the aforesaid reissued Letters Patent.

The extremities of the side beams are connected together by end frame members 6, shown best in Figs. 3, 4 and 5. These 95 end frame members have channel extremities 7 with a portion 8 of each channel extending lengthwise of the beam 1 or 2 and supported by it. These beams 1 and 2 are angle bars each with an upstanding web 9 and a lateral 100 web 10. The upstanding web 9 has an angle continuation 11 at each end bent into parallelism with an upstanding web 12 of the end portion 7 and the two webs 9 and 12 are joined by bolts 13 with the beams 1 and 2 105 electrically insulated from the respective

members 6 by interposed insulation 14. The extension 8 of each member 6 is secured to the upstanding web 9 of the corresponding frame beam 1 or 2 by a bolt 15, electrically 5 separated from the parts it connects by insulation 16.

Rising from each channel end 7 of each end frame 6 is a post 17 having a connecting brace 18 leading from its upper end to the 10 adjacent web 9, thereby strengthening the construction. The brace 18 is joined to the web 9 by a bolt 19 with interposed insulation 20 so that there is no electrical connection 25 between the brace 18 and side beam 1 or 2 15 as the case may be.

The posts 17 serve as guides for blocks 21 (Fig. 4) near opposite ends of truck beams 22 extending beyond the extremities of the end frames 6 of the main frame and there 20 carrying wheels 23 for running upon the track rails 5, whereby the track-drilling machine may be transported from place to place. Rising from each truck beam 22 near one end thereof is an upright 24 with a recess 25 at the upper end receiving a corresponding end of a rock shaft 26 and constituting a journal bearing therefor, bolts 27 serving to detachably retain the rock shaft 26 in its bearings.

30 Fast on the shaft 26 are rock arms 28 lodged between spaced parts of the upright 24. Each rock arm 28 at its outer end is connected to a link 29 by another link 30 pivoted upon the end frame 6 near the corresponding end of the latter. Each truck beam 22 is of double construction so that the links 29 and 30 extend between the two members of each truck beam. Pivoted between these members is a rock lever 31 having one 40 end connected to the link 30 and the other end connected by a similar link 32 to one end of another rock lever 33. The second rock lever 33 is connected by a link 34 to the end beam 6. The construction is such that when 45 the shaft 26 is rocked in one direction or the other both end frames 6 are raised or lowered through the link and lever mechanism.

In order to facilitate rocking of the shaft 26 it carries a manipulating lever 35 at an 50 appropriate point with a latch member 36 under the control of another manipulating lever 37 on the lever 35. The latch 36 is provided with a nose 38 arranged to engage under a catch 39 to hold the main frame and 55 parts carried thereby in an elevated position, so that they are supported by the wheels 23 out of operative relation to the tracks so far as drilling in concerned whereupon the machine may be readily moved from place to 60 place. In order to further brace the upper ends of the posts 17 the members 18 close to where connected to the posts 17 are joined together by rods 40.

Lodged in each channel end 7 of each end 65 frame 6 is a block 41 through which is

threaded a set screw 42 designed to be moved toward the rail 5, so as to determine the approach of the corresponding end of the main frame to the rail 5 for a purpose which will hereinafter appear.

Extending through each frame 6 near the main beams 1 and 2 are clamp members 43 which may be in the form of bars with downturned ends 44 suitably positioned, when the main frame is resting on the rails, 70 to engage the outer sides of the treads of the rails 5 for a purpose which will hereinafter appear. The frames 6 have slots 45 there-through traversed by and guiding the bars 43.

Near each end of the main frame is a rock shaft 46 mounted in journal bearings 47 insulated from the longitudinal beams 1 and 2 and near each end provided with a rock arm 48 to which a corresponding one of the 85 clamp bars 43 is pivoted. At one end of the shaft 46 there is secured thereto a manipulating lever 49 with a thumb latch 50 with which latter there is associated a rack segment 51 so that the rock shaft 46 may be 90 adjusted to different operative positions. By this means the clamp bars 43 are brought into clamping relation with a corresponding rail 5 or moved away therefrom as desired.

Mounted about midway of the length of 95 the main frame to one side of the division line between the two sections of the main frame is a power unit 52 which may be considered as an internal combustion engine of any suitable type and therefore requires no 100 specific description.

The engine 52 is provided with a main or power shaft 53 carrying a pinion 54 meshing with a gear wheel 55 on a countershaft 56, which latter is journaled in the two members 1 and 2 of the main frame. Extending lengthwise of and journaled in the longitudinal center line of the main frame are countershafts carrying terminal bevel gears 57 together meshing with a bevel pinion 58. 110 The shafts carrying the bevel gears 57 each carrying another gear wheel 59 in turn meshing with a pinion 60 on a drill shaft 61, there being two such drill shafts in alignment one with the other and extending 115 lengthwise of the main frame. The two shafts are driven in reverse directions by the bevel gears 57, 58 and are speeded up by the multiplying gearing 59 and 60. Each shaft 61 while constrained to rotate by the pinion 60 is free to move lengthwise through the pinion. Each shaft is, furthermore, supported near the corresponding outer end of the main frame by a journal bearing in a bracket 62 depending from one of the cross 120 beams 3 of the main frame. At the end of the shaft 61 remote from the pinion 60 is a drill chuck 63 in which may be mounted a suitable drill 64 of a size to bore a hole 125 through the web of the adjacent rail 5 for 130

receiving a double channel pin and rail bonds, in accordance with the present day practice.

Each shaft 61 at an appropriate point 5 passes through a thrust bearing 65, one of which is shown in detail in Figs. 7, 8, 9 and 10. Each thrust bearing comprises a sleeve 66 held between end plates 67, 68 by bolts 69. The shaft 61 has fast to it by a pin 70 or 10 otherwise a block 71 capable of rotating within the sleeve, and between each end of the block 71 and the corresponding plate 67 or 68, are ball bearings 72. This structure permits the shaft even under the thrust of 15 drilling to rotate with the greatest ease and offer little resistance to such rotation.

The plate 68 has an arm 73 projecting from one side thereof, this arm being upright in the installed position and carried by another arm 74 depending from a collar 75 20 carrying and forming the journal bearing for a shaft 76 having rollers 77 at the ends traveling on the webs 10.

Depending from the main beams 1 and 2 25 are brackets 78 to which are pivoted the lower ends of upright hand levers 79 having hand latches 80 at their upper ends arranged to move over the opposite edges of a platform 81. The latter is erected on posts 82 which rise from appropriate parts of the 30 main frame and it overrides the engine 52. The arrangement is such that the levers 79 and the handle 35 are within easy reach of an operator controlling the engine 52. Each 35 lever 79 is connected by a link 83 to a corresponding one of the thrust bearings 65 so that either or both drills 64 may be advanced to the work or withdrawn therefrom at the will of the operator.

40 The shaft 26 has its electrical continuity broken by insulation 84 and the two ends of the shaft are joined by a sleeve 85, so that the mechanical continuity of the shaft is intact.

45 In order to avoid any possibility of stray currents reaching the engine and so causing charges therein to explode out of time, the engine is insulated, as shown at 86 from the main frame and also at the pinion 54 as 50 shown at 54^a in Fig. 1.

The operation of the present machine is similar to that of the patented machine and therefore requires no particular description. The height of the drills with respect to the 55 rails may be determined by the adjusting screws 42, limiting the drop of the main frame toward the rails. The feed of each drill with respect to the rails is controlled by the respective lever 79 through the thrust 60 bearing 65 which is supported by the side beams 1 and 2 and travels on the webs 10 thereof through the rollers 77, the friction of the thrust being reduced in both directions of movement by the ball bearings 72 65 at opposite ends of the block or collar 71.

Liability of the machine bridging the rails when the rails are charged for signal purposes is overcome by insulating the two ends of the drilling machine from each other and any liability of stray currents affecting the prime mover is avoided by insulating the latter from its supports on the main frame.

By causing the clamp bars 43 to traverse the end bars 6 these bars 43 are supported and considerable mechanism employed in the structure of the patented machine is avoided.

What is claimed is:—

1. A drilling machine for rails of tracks, comprising drilling mechanism, a main supporting frame for the drilling mechanism, and end frame members at the ends of the main frame having track-engaging means for carrying the latter, said end frame members and main frame being constructed of separate elements connected together and electrically insulated one from the other at all their points of connection, the ends of said main frame where connected with the end frame members being spaced from the track rails, whereby short circuiting of signal currents is prevented.

2. In a drilling machine for the rails of tracks, a main frame comprising beams spaced apart lengthwise of the track and connected together, end frame members having track-engaging means, and each formed of a separate piece from the main frame, means for connecting the ends of the beams to the end frame members and insulating the frame members from the beams, said frame members having slots, clamping members for the rails passed through said slots, a rock shaft at each end of the main frame to which the clamping members are connected, means for operating each rock shaft, and bearings for said rock shaft fastened to said beams and insulated therefrom.

3. In a drilling machine for the rails of tracks, a main frame comprising beams spaced apart lengthwise of the track and connected together, end frame members having channel extremities, each end frame member being formed of a separate piece from the beams, means for connecting the ends of the beams to the end frame members at two points, one connection for each beam being at the end of the end frame and the other at an intermediate point thereof and both connections being away from the channel extremities, means for insulating the beams from the end frame members at the several points of connection, posts rising from each channel extremity, track beams carrying wheels to run on the track and guided by said posts, and means for raising and lowering said track beams.

4. In a drilling machine, a main frame comprising side beams of angle construction, end frame members separate from the side

beams and extending laterally beyond the side beams and there of channel construction, guide posts carried by the channel ends of the end frame members, trucks traversed 5 and guided by the guide posts, and adjusting means carried by the trucks and channel portions of the end frame members and connecting the trucks and end frame members together, the adjusting means including ma- 10 nipulating parts carried by the side beams, the side beams being electrically insulated from the end frame members and the said adjusting means.

5. In a drilling machine for the rails of tracks, a main frame comprising beams spaced apart lengthwise of the track and connected together, end frame members having channel extremities, each end frame member being formed of a separate piece 20 from the beams, means for connecting the ends of the beams to the end frame members at two points, one connection for each beam being at the end of the end frame and the other at an intermediate point thereof 25 and both connections being away from the channel extremities, means for insulating the beams from the end frame members at the several points of connection, and track-engaging means connected with the end 30 frame members for carrying the latter.

6. In a drilling machine, a main frame comprising side beams of angle construction, end frame members separate from the side beams and extending laterally beyond the 35 side beams and there of channel construction, guide posts carried by the channel ends of the end frame members, trucks traversed and guided by the guide posts, adjusting means carried by the trucks and channel 40 portions of the end frame members and connecting the trucks and end frame members together, blocks lodged in the channel extremities, and set screws threaded through the blocks and said channel extremities and 45 adapted to engage the head of the rail for the purpose set forth.

7. A drilling machine for the rails of tracks, comprising a main frame having end frame members extending laterally of the 50 main frame and in the direction of the length of the track and having slots, drilling means on the main frame for drilling the web of the track, and clamping means for opposing the thrust of the drilling

means and comprising clamp bars extended 55 through the slots and supported by the end frame members and provided with down-turned extremities for engaging that side of each rail remote from the drilling means, the clamp bars being arranged in close relation to the sides of the main frame, and a rock shaft and adjustable manipulating holding means therefor connected to the clamp bars for moving the latter longitudinally and in transverse relation to the 60 track.

8. In a drilling machine for the rails of tracks, a main frame with side beams having substantially horizontal longitudinal webs, a shaft extending between the side 70 beams and provided with end rollers for traveling on the flanges, and carrying means in pendant relation to the shaft and carried thereby, a thrust member on the carrying means and provided with antifriction bearings at both ends, and a drill extending through the thrust member.

9. In a drilling machine for the rails of tracks, a main frame having spaced 80 side members with substantially horizontal longitudinal webs, a thrust bearing provided with supporting devices and rollers with the latter engaging the webs to travel therealong, manipulating means for the thrust bearing, and a drill shaft extending 85 through and constrained to move longitudinally by the thrust bearing and the manipulating means therefor.

10. In a drilling machine for the rails of tracks, a main frame having longitudinal 90 beams providing tracks, a drill shaft, a thrust bearing surrounding the latter at an appropriate point of its length, a shaft having end rollers to run on said tracks, a collar forming a journal bearing for the last-mentioned shaft, an arm depending from the collar and rigidly secured to said thrust bearing, a hand lever, and connections between said hand lever and said thrust bearing.

In testimony that I claim the foregoing as my own, I have hereto affixed my signature in the presence of two witnesses.

JOHN J. LONSWAY.
